UNITED STATES PATENT OFFICE

EDWARD S. HALSEY, OF MIAMI SHORES, FLORIDA

ROOM-TEMPERATURE-REGULATING AIR VALVE

Application filed February 6, 1930. Serial No. 426,286.

The invention concerns means for controlling the heating operation of a radiator according to room temperatures, said means being coupled not to the steam inlet end of the 5 radiator but to the vent end, so as to control the outlet of air therefrom or its inlet thereto whereby the steam supplied to the inlet end of the radiator is allowed to enter the same or is prevented from gaining an entrance to 10 the radiator, in response to fluctuations of steam pressure, above and below that of the atmosphere.

The invention consists in the features and construction and arrangement of parts hereinafter described and particularly pointed out in the claims.

In the drawings:

Fig. 1 is a vertical section through a portion of a radiator and an attachment embodying the invention;

Fig. 2 is a plan view partly in section;

Figs. 3 and 4 are views in section relating to the thermostat;

Fig. 5 is an end view of the thermostatic 25 unit;

Fig. 6 is a detail sectional view of Fig. 2 on line 6—6;

Fig. 7 is a view of a modified embodiment 30 of the invention;

Fig. 8 is a sectional view of a modified form 35 of the control valve;

Fig. 9 is a view of the means for creating variations in the steam pressure;

Fig. 10 is a view of a modified means for 40 creating variations in the steam pressure; and

Figs. 11 and 12 are views of details.

In the drawings 1 indicates what is usually 45 the vent end of the radiator where ordinarily a vent valve is provided for the escape of air from the radiator.

Into the opening 2 is screwed a nipple 3 of the valve casing. This is made up of a lower portion 4 of substantially cup shape 50 into the top of which is screw threaded a shell 5, open at its upper end and receiving a thin metallic shell 6 which is forced down into the main shell with a tight fit. Suitable packing is arranged at 7 to make a steam tight seal. The inner shell 6 is closed at its

upper end. The lower edge portion of this inner shell is reduced in diameter to provide a depending flange 8, the edge of which forms an upper seat for a valve disc 9 of rubber, mica, or other suitable material. Said 55 valve disc is thin and flexible and is reinforced by dished plates 10 and 11, which diverge from each other at their edges so that the disc valve may flex in finding a close fit with its seat. There is provided also a lower 60 seat 8a for the valve disc 9 said seat being formed by an upstanding rim or flange on the main body 4 of the casing. The valve means 9 is provided with an ear 12 to which is attached a wire or rod 13 connected to an arm 14 extending out through an enlarged opening 15 of the casing. This arm is connected with arm 16 which is connected with the shaft 17 of the thermostat which is exposed to the temperature of the room, the construction 65 of the thermostat being such, as hereinafter described, that when the temperature of the room rises above normal then the connections described will be operated so that the disc valve will be raised against the upper seat 70 8 against which it will loosely or lightly bear. When, on the other hand the temperature of the room is sub-normal then the shaft 17 of the thermostat will be rotated in a direction opposite to that under super-normal 75 temperature conditions and the disc valve on line 8 will be lowered to rest loosely or lightly upon its lower seat 8a. The opening 15 in the side of the casing communicates with the atmosphere and for this purpose the main 80 shell is slotted at 15a.

The sensitivity of the thermostat can be such that the entire movement of the valve will take place during a variation of one degree in temperature.

While the valve is resting on its upper seat as a consequence of the super-normal temperature of the room as above referred to and the radiator is under pressure i. e. with steam above atmospheric pressure no air can escape from the radiator, but upon slight recessions of this pressure then the air will enter the radiator. In this action the valve disc will move from its upper seat and allow air to enter the radiator which will occupy space 95 100

therein displacing the steam and thus acting to cool the radiator.

Now when a subnormal temperature of the room is reached and the valve disc lies on its lower seat 8a the inlet of air to the radiator past the valve 9 will be no longer possible upon recessions of pressure thus retaining its steam and temperature. Air, however, can escape from the radiator on slight rise of pressure owing to the valve moving upwardly from its lower seat under said slight rise of pressure. The valve disc 9 is of comparatively large diameter and its large area facilitates the actions above described. The valve when on its upper seat acts as a check against outflow of air from the radiator while allowing air to enter under recessions of pressure within the radiator to displace or hold back the steam to lower the room temperature. On the other hand when on its lower seat the valve disc acts as a check against inlet of air to the radiator under recession of pressure within the radiator while allowing the air to freely escape from the radiator for the inlet of steam to raise the room temperature.

30 There is also provided within the valve casing a partition 18 with a small central aperture 19. This is controlled by a valve 20 on a float or dilating member 21 so that if steam or water tends to rush out through the connection 3 from the radiator the upper wall of the member will rise and the float 21 will rise as a body and the opening 20 will
35 be closed.

This is the opening through which the radiator is placed in communication with the atmosphere, but under control of course of the disc valve 9. This float is a hollow body containing an alcohol vapor charge. It will dilate under steam temperatures and check the outflow of steam. It is buoyant so that it will quickly rise if water appears.

45 The thermostat may be of various forms. The form shown includes the shaft 17 to which the bi-metal thermostat coil 17a is attached. This coil is sensitive to temperature changes and under a rise of temperature in the room it will rotate the shaft 17 one way and under a fall of temperature it will rotate the shaft the other way. The coil and shaft arrangement is illustrated in detail in Figs. 3 and 4. They are enclosed in a tubular casing 22 held by brackets 23 extending 50 from a shield or heat insulating base plate or board 24 say of bakelite supported by a bracket 25 partly encircling the cylindrical casing of the valve mechanism.

60 Adjustment of the coil can be effected by turning the finger button 26 having its central sleeve portion 27 journalled in the casing 22, said sleeve having a plug 28 affixed thereto to which the coil is attached.

The finger piece may be graduated as at 29
65 so that desired adjustment may be secured

relative to a pointer 30. Stops are provided at 31 to come against the frame part 32.

The thermostat is arranged horizontally and transversely of the end of the radiator. It extends about equally on opposite sides of the central vertical plane of the radiator. This thermostat is relatively feeble but active. It has a movement of about $\frac{1}{2}$ of an inch per degree. As above stated the thermostat coil is arranged with its axis horizontally and the connection between this horizontal coil and the valve is such that the valve will be held lightly on either seat, but will be capable of movement off from either seat, under the conditions above secured, the coil yielding by a slight winding or unwinding movement as the case may be in the actions described. In other words the valve is double acting in that it is placed on either its upper or lower seat by the action of the thermostat and when on either seat it will prevent flow of air past it in one direction but will allow passage of air in another direction, said valve for the latter purpose moving from its seat and the thermostat coil yielding circumferentially to permit these actions.

Any suitable means may be employed for locking the appliance to the radiator, such for instance as the clamps shown at A. This involves any desired means for locking a retainer screw in place so that considerable work would have to be performed in order to remove the appliance and this would deter casual theft of the appliance. 95

In Fig. 7 I show the attachment mounted on top of the usual vent valve casing 33 which as in former practice is screwed into the vent of the radiator. 100

I show in Fig. 8 a modified form of valve, where instead of using a disc of flexible material I employ a body 9a of double conical form to seat either at its upper or lower ends, said seats being indicated at 8x and 8y. This valve is connected either to the thermostat in the same manner as above described by a rod 13 and arm 14 passing through the air port 15, and its action is substantially the same as that described in the first form of the invention. The valve is located in a supplemental housing b and is provided with a disc c of a diameter to fit fairly close within the housing. This disc increases the sensitivity of the valve and steadies it in its operation it having a piston like action in the housing. In this form the float or dilating or expandible member 21a acts directly against the valve and closes it against its upper seat on attempted outflow of steam or water. While the valve medium above described will operate through the material fluctuations in pressure in the ordinary domestic heating system which at intervals falls to or slightly below atmospheric pressure and under the damper influence again rises to a moderate pressure above atmosphere, means may be

used in connection with a system employing my improvement set forth above for creating intermittently rises and recessions of the pressure within the system, from slightly 5 below atmosphere pressure to a pressure of one pound or so.

In Fig. 9 I show such means in which 34 is the steam riser pipe from boiler 35. At 36 is a weighted lever pivoted at 37, and connected at its ends with the furnace damper 38 and check 39 respectively as in usual practice. This lever has an upstanding ear 40 adjacent the pivot 37 and a spring 41 is connected with the upper end of this ear and 15 with a point on the pivot so that when the lever is tilted either one way or the other to move the upper end of the spring slightly beyond the vertical plane in which the pivot 37 and the lower end of the spring lie, the 20 said spring will exert a retarding force and suddenly move the lever to its extreme limit thus adjusting the damper and the check to bring on suddenly a change in the draft and check condition to thereby quickly change 25 the operation of the furnace to increase or reduce pressure as the case may be. The lever is operated by a sylphon bellows at 42.

In Figs. 10 to 12 I show another means for producing the fluctuations in pressure. In 30 this form the riser pipes *a*, *b*, *c*, *d*, say four in number, branch off from a central riser 34*a*, each riser supplying steam to the group of radiators in its respective quarter. At the junction of these pipes there is a casing 43 Fig. 12 containing a loose fitting rotary valve 44 which as it rotates partially closes for a brief period and in succession the series pipes 45 *a*, *b*, *c*, *d*. This valve is on a vertical shaft which is driven by any suitable means from 40 a motor as shown for instance by a Geneva movement 46 Fig. 11. By this means the valve when it closes either of the pipes *a*, *b*, *c*, *d*, against the passage of steam there- 45 through from the boiler to the correspond- ing group riser will dwell in its closed position with the result of cutting off the steam periodically and for a prescribed time from each riser, thus creating the desired fluctuations for the operation of the automatic con- 50 trol of each successive groups of radiators. It is obvious that many other simple means could be employed to bring about this desired intermittent recession of steam pressure, such for instance as accumulating the return 55 water from the mains in an automatic dumping trap, arranged to periodically and suddenly discharge its cooled water into the boiler, as often as it became filled from the return pipes feeding into it, thus momentarily 60 cooling down the boiler. Instead of mount- ing the valve at the vent side of the radiator where at times the last section or sections are cold and at other times hot thus giving rise to varying air currents which might affect 65 the thermostat undesirably, I may mount

the valve mechanism at the inlet end of the radiator where it will be subject to more uniform influence of the room temperature or air currents, this inlet end of the radiator when in service being substantially uniformly heated. When so mounted at the inlet end of the radiator the valve mechanism is connected with the vent by a pipe *e* so that the venting action of the valve mechanism is the same as when mounted directly at the vent. 70 The bakelite block in any event acts as a shield against radiated heat and as an insulator against heat conducted in respect to the thermostat.

I claim:

1. A control valve for radiators and in combination therewith a casing connected to the air vent of the radiator, a valve therein to control the passage of atmospheric air to the radiator and the discharge of air from the radiator to atmosphere, a room thermostat for controlling the said valve means for supporting the thermostat on the valve casing to be handled therewith as one unit, and means for transmitting movement from the thermostat to the valve. 80

2. A control valve for radiators comprising a casing connected to the air vent of the radiator, a valve therein, a room thermostat with an actuating connection operated thereby for setting said valve in one position under super-normal room temperature and for setting said valve in another position for sub-normal room temperature, said valve under the super-normal condition acting as a check valve against outflow of air from the radiator to atmosphere while allowing inflow of atmospheric air thereto and under sub-normal temperature condition acting as a check against inflow of atmospheric air to the radiator while allowing outflow to atmosphere of air from said radiator substantially as described. 95

3. A control valve according to claim 2 comprising a body to which the thermostat is connected and a valve seat above and below said valve in relation to which the said valve may move to allow the passage of air, substantially as described. 100

4. In combination with a valve casing to be connected to the vent of a radiator, a valve therein controlling said vent, a room thermostat and an actuating connection extending from said thermostat through an opening in the valve casing to the valve to transmit motion from the thermostat to the valve, said opening allowing ingress and egress of air to and from the radiator under control of said valve substantially as described. 115

5. In combination a valve casing to be connected to the vent of a radiator, an apertured partition in said casing, a float valve in the casing controlling said aperture, a valve above said partition, a seat above and a seat below said valve, a thermostat exposed to 120 125

room temperature and connected with said valve, said valve when on its upper seat preventing discharge of air from the radiator while allowing access of atmospheric air thereto and while on its lower seat checking flow of air into the radiator while allowing the passage of air therefrom to atmosphere substantially as described.

6. In combination, a main casing having a 10 nipple for connection with a radiator, an upper casing section seated on the casing first mentioned, a casing section fitted into the upper casing section and having a flange of reduced diameter forming an upper seat for 15 the valve, said main casing having a lower seat for the valve, a valve member operating between said seats and a thermostat exposed to room temperature and connected to the valve for operating it substantially as described.

7. In combination with a radiator, a valve mechanism connected with the vent of said radiator comprising a valve to control said vent, a room thermostat controlling the 25 valve, and means for creating fluctuations of pressure within the radiator in addition to fluctuations inherent in such systems.

8. An apparatus of the class described, a double acting valve resting on a seat to prevent access of atmospheric air to the radiator while allowing discharge of air to atmosphere during subnormal room temperatures and resting on another seat during supernormal room temperatures to prevent escape 35 of air to atmosphere from the radiator while allowing inlet of atmospheric air thereto, and a room thermostat controlling said valve.

9. In combination, a valve casing to be connected to the vent of a radiator of a heating 40 system, a valve in said casing to control the passage of air to and from the radiator, a room thermostat connected with the valve to close it upon either one of two seats according as the room temperature is above or below 45 normal, said valve in either position serving as a check to prevent passage of air in one direction but opening automatically for the passage of air in the other direction, the thermostat yielding to allow the last mentioned action to take place.

10. Apparatus according to claim 2 in which the thermostat connection will yield to allow the valve to open automatically from either of its seats under pressure of air substantially as described.

11. Apparatus according to claim 2 in which the thermostat is in the form of a coil which in winding moves the valve upon one seat and in unwinding moves the valve upon 50 the other seat, said valve opening from either seat automatically under air pressure, the said thermostatic coil yielding by winding or unwinding for said automatic action of the valve substantially as described.

12. Apparatus according to claim 2 in

which the valve operates vertically and the thermostat is in the form of a helix the axis of which extends horizontally.

13. Apparatus according to claim 1 in which the thermostat is in the form of a helix 70 extending with its axis horizontally.

14. A room temperature regulating air valve means for radiators comprising a frame having means for attachment to a radiator, and a room thermostat mounted on the said 75 frame for controlling the valve, said valve in turn controlling the air vent of the radiator, heat insulating means also mounted on the frame all said parts forming one unit for attachment to or removal from the radiator 80 as one body.

In testimony whereof, I affix my signature.
EDWARD S. HALSEY.
